UNITED STATES PATENT OFFICE.

JAMES C. RAMSEY, JR., OF ANDOVER, MASSACHUSETTS, ASSIGNOR, BY MESNE ASSIGNMENTS, TO AIKEN LAMP COMPANY, OF FRANKLIN, NEW HAMPSHIRE.

LAMP-SUPPORT.

1,147,973.

Specification of Letters Patent. Patented July 27, 1915.

Application filed October 31, 1912. Serial No. 728,822.

To all whom it may concern:

Be it known that I, JAMES C. RAMSEY, Jr., a citizen of the United States, residing at Andover, in the county of Essex and State 5 of Massachusetts, have invented a new and useful Lamp-Support, of which the following is a specification.

This invention relates to a supporting and operating device for an electric lamp for use 10 on automobiles and the like.

The principal objects of the invention are to provide a simple and inexpensive construction by which the lamp can be controlled and especially by which it can be 15 turned about two axes transverse to each other by a simple rotary motion of a handle to secure one turning motion and by reciprocation of the handle or a part thereof to secure the other turning motion.

20 The invention also involves improvements in details of construction and combinations of parts as will appear hereinafter.

Reference is to be had to the accompanying drawing, in which—

25 Figure 1 is a side view of a part of an automobile showing how a preferred form of this invention can be applied thereto; Fig. 2 is a central vertical longitudinal sectional view of the lamp support; Fig. 3 is 30 central longitudinal sectional view at right angles thereto; and Fig. 4 is a sectional view on the line 4—4 of Fig. 2.

The invention is shown as applied to the 35 dash of an automobile. For this purpose a support 10 is provided extending up from the dash and having a horizontally extending end or pivot 11. This is provided with a circumferential groove 12 and on it fits a hub on a frame 13. This frame is provided 40 with a screw 14 projecting into the groove 12 so that the frame can be turned on the cylindrical end 11 as a pivot. The hub which fits on this pivot is slit longitudinally 45 and in order to secure it in fixed position on the pivot a collar 15 is provided having a set screw 16 for tightening it. The pivot is lubricated preferably by a piece of felt or wick 17 located in a slot in the hub and held in place by a plate 18.

50 The member 13 is supplemented by a second member 20 and these together form a hollow casing or frame for some of the operating parts of the device. Extending from this casing is a hollow handle 21 through 55 which projects a hollow rod 22. On the end

of this rod is a hand-hold 23 for manipulating it, and it fits in a bushing 24 at the end of the handle. The rod 22 enters a guide slot 24^a at the other end of the casing and is provided with a rack 25 which meshes with 60 a pinion 26 on a shaft 27 supported in bearings in the casing and projecting from the top thereof. On this shaft is fixed a hub 28 which constitutes an extension of the lamp casing 29. Through this hub extend the 65 wires 30 for conducting a current to the lamp, and these wires are connected through an opening 31 in the shaft and an opening 32 in the rod with a push button construction 33 on the hand hold. They then pass 70 down through the support 10. In this way the wires are entirely inclosed and concealed, and so are the other working parts.

The operation is very simple. If it is desired to turn the lamp about the horizontal 75 pivot 11, this is done simply by swinging the handle through the desired arc. If the lamp has to be turned on a vertical axis or an axis transverse to the axis of the pivot 11, the hand-hold is simply moved in or out 80 as the case may be, to turn the shaft 27 and thus swing the lamp. The two parts of the casing can be taken apart very easily for inspection and repairs. Thus a very simple device is provided for this purpose, and 85 capable of swinging the lamp through a wide arc on its vertical axis and through an unlimited arc on its horizontal axis.

While I have illustrated and described 90 only one form of the invention I am aware 90 of the fact that modifications can be made therein by any person skilled in the art without departing from the scope of the invention as expressed in the claims. Therefore, I do not wish to be limited in these 95 respects, but

What I do claim is:—

1. In a device of the character described, the combination of a lamp frame mounted to turn about a horizontal axis, said frame being provided with a rigid handle projecting therefrom by which the frame can be turned about said horizontal axis, a rod movable longitudinally along the handle, a lamp casing mounted above said frame, and means whereby the reciprocation of said rod will turn the lamp casing on said frame on an axis at an angle to said horizontal axis. 100

2. In a device of the character described, the combination of a lamp frame arranged 105

to turn about a horizontal axis, said frame being provided with a handle projecting therefrom by which the frame can be turned about said axis, a shaft carried by said frame, a rod movable longitudinally along the handle, means whereby the reciprocation of said rod will turn said shaft on an axis at an angle to said horizontal axis, and a lamp casing fixed with respect to said shaft, said shaft and rod being provided with passages for conducting wires to the lamp.

3. In a device of the character described, the combination of a lamp frame mounted to swing about a horizontal axis, said frame being provided with a handle projecting therefrom by which the frame can be turned about said horizontal axis, a rod movable longitudinally along the handle and having a rack thereon, a pinion meshing with said rack, a shaft on which the pinion is located, a lamp casing fixed with respect to said shaft, said shaft and rod being provided with passages therethrough for the conducting wires to the lamp, and a support for the

frame having a passage therethrough for the conducting wires.

4. In a device of the character described, the combination of a lamp frame mounted to turn about an axis, said frame being provided with a hollow handle projecting therefrom by which the frame can be turned about said axis, a hollow rod movable longitudinally in the handle and having a push button and a rack thereon, a pinion meshing with said rack, a hollow shaft on which the pinion is located, a lamp casing fixed with respect to said shaft, a support for the frame having a passage therethrough, and conducting wires passing from the lamp through the shaft, and rod to said push button, and through the rod and support from said push button.

In testimony whereof I have hereunto set my hand, in the presence of two subscribing witnesses.

JAMES C. RAMSEY, JR.
